CLAIM

The ornamental design for a rubber strip, as shown and described.

DESCRIPTION

FIG. 1 is a front view of a rubber strip showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a first perspective view thereof; and,

FIG. 8 is a second perspective view thereof.
